SNATCH BLOCK

Bert B. Bryson and Marion Alvin Coleman,
Kilgore, Tex.

Application August 27, 1947, Serial No. 770,910

5 Claims. (Cl. 254—193)

1

This invention relates to an improved snatch block and more particularly to a device of this kind having swingable side plates which are adapted to be locked in the closed or engaged position by a pivotal trunnion bolt.

An object of this invention is to provide an improved snatch block in which the side plates may be pivotally separated about a connecting bolt for ready insertion of a cable or the like between the side plates where the cable is trained over a pulley or sheave supported therebetween.

Another object of this invention is to provide a snatch block of this kind in which the side plates are locked in erect position or closed position by engagement of one of the side plates with a slotted trunnion bolt on which is supported a hook. In one position of the trunnion bolt the side plates are so engaged that they are securely locked together, while in another position of the trunnion bolt substantially 90° from the first position, the side plates may be pivotally separated.

With the above and other objects in view, our invention consists in the arrangement, combination and details of construction disclosed in the drawings and specification, and then more particularly pointed out in the appended claims.

In the drawings,

Figure 1 is a side elevation of a snatch block constructed according to an embodiment of our invention,

Figure 2 is a front elevation, partly broken away and partly in section,

Figure 3 is a side elevation, partly broken away and partly in section, of the snatch block with the plates in the separated position,

Figure 4 is a fragmentary detail transverse section taken on the line 4—4 of Figure 1,

Figure 5 is a fragmentary section taken on the line 5—5 of Figure 4,

Figure 6 is a top plan view showing the relation of the trunnion bolt and engaging pivot pin.

Referring to the drawings, the numeral 10 designates generally an improved snatch block in which the side plates may be pivotally separated for the insertion or removal of a cable or other flexible member between the plates, for engagement with a pulley supported between the plates. The snatch block 10 is so constructed and arranged that the side plates 11 and 12 will be locked together in one position of a trunnion bolt 14 which connects the side plates 11 and 12 together at their upper end.

In a position of the trunnion bolt 14 rotated substantially 90° from the locking position, the

2

side plates 11 and 12 may be pivotally separated at their upper ends by rocking in either direction from the trunnion. This construction and arrangement is particularly adapted for use of a snatch block in restricted areas in which it will be necessary or desirable to have the plates separable by rocking in either direction from their fixed position. Such a construction will eliminate the necessity of removing the snatch block from its supporting cables or the rotation of the snatch block to dispose it in a certain position so that the cable may be removed or inserted.

The side plates 11 and 12 are formed with an opening near their lower end through which a pivot pin 15 is loosely engaged. The pivot pin 15 is formed with an enlarged shank 16 which engages through the opening of one side member, as 12, and is formed with a reduced diameter threaded end 17 by engaging through the opening in the other plate 11.

A flange or head 18 is formed on the end of the shank 16 for abutting engagement with the outside surface of the plate 12. A nut 19 is threadably engaged on the reduced diameter end 17 for abutting engagement with the outside of the plate 11 for pivotally connecting the plates together at their lower end. A pulley or sheave 20 is rotatably supported on the pin 15 between the plates 11 and 12. The pin 15 is formed with a lubricating opening 21 which opens at one end as through the head 18 and opens intermediate the length of the shank 16 for lubricating the bearing surface between the pin and the pulley 20.

The upper end of one plate, as plate 12, is slightly offset as indicated by the numeral 22, to provide sufficient space and clearance at the upper end of the plates 11 and 12 for disposition of the trunnion bolt 14 and its engaging pin 24. The trunnion bolt 14 is rotatably supported from one of the side plates 11 at the upper end thereof. The bolt 14 is substantially cylindrical in shape, having a pair of opposed flattened surfaces, as 25, 26, on opposite sides thereof.

A reduced diameter trunnion bearing 27 is fixed to or formed on one end of the trunnion bolt 14 adjacent one flat surface, as the upper surface 26. The bearing surface 27 engages through an opening 28 in the side wall of the plate 11. A reduced diameter threaded bolt 29 is fixed to or formed on the end of the bearing 27 concentric thereto and a nut 30 is threadably engaged with the bolt 29 for rotatably securing the trunnion 14 on the plate 11.

A cotter pin 31 engages through the nut 30 and bolt 29 for holding the nut against rotation on the bolt. A U-shaped opening 32 is formed on the other end of the trunnion 14 and opens upwardly through the end of the upper flat surface 26. The opening 32 also opens outwardly through the outer end of the bolt 14. The bolt 14 is further formed with a recess 33 inwardly of the opening 32, thereby forming a flange 34 about the opening 32 at the end of the bolt. The flange 34 is substantially U-shaped and extends about the edge of the opening 32. The lower end of the opening 32 and flange 34 is arcuate, having a radius substantially the same and coaxial with the bearing 27 on the opposite side of the trunnion.

A trunnion engaging pin 35 is rotatably supported in the opposite side plate 12 adjacent the upper end thereof. The side plate 12 is formed with an opening 36 through which the pin 35 loosely engages. The pin 35 is formed with an enlarged annular head or bearing surface 37 which is adapted to abuttingly engage the inner surface of the plate 12 and engage on the upper edge of the flange 34 in the opening 32. The bolt 35 is coaxial with the bearing 27 to provide a pivot for the trunnion 14. The shank of the bolt 35 engages through the opening 36, and a nut 38 threadably engages the shank 36 outwardly of the plate 12 where it is secured by a cotter pin 39.

An enlarged diameter flange 40 is fixed to or formed on the inner surface of the head 37 concentric thereto. The flange 40 is provided for engagement within the recess 33 in the opening 32 of the trunnion 14. The flange 40 and head 37 on the bolt 35 engage only the bight or arcuate surface of the U-shaped opening 32 and flange 34.

A supporting hook 41 is carried by the trunnion 14 and extends normally above the upper end of the plates 11 and 12. The hook 41 is formed with a reduced diameter shank 42 which engages through the trunnion bolt 14 intermediate the length thereof. The shoulder 44 formed by the reduced diameter shank 42 and the upper portion of the hook 41 abuttingly engages the upper flat surface 26 of the bolt 14. A nut 45 threadably engages the lower end of the shank 42 below the bolt 14 and is adapted to abut the lower flat surface 25 thereof.

In the use and operation of this snatch block 10 the side plates 11 and 12 are adapted to be hooked together through the trunnion bolt 14 in the erect position of the hook 41. For separating the side plates 11 and 12 it is necessary to rock the hook 41 substantially 90° so that the opening 32 will be disposed approximately perpendicular to the vertical axis of the side plates. Rocking of the hook 41 will effect simultaneous rocking of the trunnion bolt 14 so that the bearing 37 and flange 34 may be slid from the opening 32 and recess 33 to one side of the axis of the plate.

For engaging the side plates 11 and 12 again, it is necessary after the cable has been removed from or inserted into engagement with the pulley 20 to pivot the plate 12 about the pivot pin 15 so that the flange 40 and bearing 37 will slidably engage into the opening 32 and recess 33. As the hook 41 and trunnion 14 are rocked or pivoted about the bolts 29 and 35, the side arms of the opening 32 will hold the pin 35 against sliding movement from the opening 32. In this manner the side plates 11 and 12 are efficiently

locked together. The construction is such that swinging movement of the plates 11 and 12 about the pivot through the bolts 29 and 35 will not permit the separation of the side plates 11 and 12 until the trunnion is rotated approximately 90° from the erect position. Seldom is such a position inadvertently attained by the snatch block in its use. To rotate the trunnion this far it is necessary to release all the tension from the snatch block and rotate the trunnion manually.

We do not mean to confine ourselves to the exact details of construction herein disclosed, but claim all variations falling within the purview of the appended claims.

Having thus described our invention, what we claim is:

1. An improved snatch block comprising a pair of parallel side plates, the upper portion of one of said plates offset outwardly from the lower end thereof, a pivot pin between the lower ends of said plates, a pulley rotatable on said pin, a hook, a trunnion rotatably mounted on one of said plates between said plates at the other end thereof, means mounting said hook on said trunnion, said trunnion formed with an upwardly and inwardly opening groove on one end thereof, a trunnion engaging pin carried by the other of said plates, an annular flange on said pin engageable in said groove, said flange slidable from said trunnion in a rotated position of said trunnion whereby said plates may be pivoted about said pivot pin for separating the plates at the upper end thereof.

35. 2. An improved snatch block comprising a pair of parallel side plates, a pulley pin between said plates at one end thereof, a pulley on said pin, at least one of said plates being loose on said pin for rotation thereabout, a trunnion between said plates at the other end thereof, said trunnion including a cylindrical body having oppositely disposed flat sides, a reduced diameter bearing at one end of said body rotatably engaging through one of said side plates, a hook on said trunnion,

40. 45. the other end of said body formed with a U-shaped recessed groove opening on one side of said body, a trunnion engaging pin carried by the other side plate, an annular flange on said trunnion engaging pin slidable into said groove through the open end thereof in one position of said trunnion, said flanged pin being restrained in said groove in other positions of said trunnion for supporting said other plate on said trunnion.

3. An improved snatch block comprising a pair of parallel side plates, a sheave supporting pin loosely engaging through said plates at one end thereof, a sheave rotatable on said pin, a trunnion rotatably mounted on the other end of one of said plates, a radially disposed U-shaped channelled groove on one end of said trunnion adjacent the other plate, opening on one side of said trunnion, a flanged pin carried by the other plate engageable in said groove, said flange engaging in said groove slidably in one rotated position of said trunnion for removal therefrom whereby said plates may be rocked in opposite directions about said sheave pin for separating the upper ends of said plate.

60. 65. 4. An improved snatch block comprising a pair of parallel side members, a pulley rotatable between said members at one end thereof, means pivotally securing said members together at one end thereof, a cylindrical member rotatably carried by one of said side members at the other end thereof, said latter member formed with a chan-

70. 75. nelled groove for receiving the other side member, the cylindrical member being rotatable in said groove for separating the upper ends of the side members.

nnelled recess at one end thereof adjacent the other side member, said recess opening radially through one side of said rotatable member, and a flanged pin on the other side member, the flange of said pin engaging in said recess for supporting the other member from said rotatable member, said flange being slideable from said recess in one rotated position of said rotatable member whereby said snatch block may be opened at one end between said side members.

5. An improved snatch block comprising a pair of parallel side members, a pulley rotatable between said members at one end thereof, means pivotally securing said members together at one end thereof, a cylindrical member rotatably carried by one of said side members at the other end thereof, said latter member formed with a channelled recess at one end thereof adjacent the other side member, said recess opening radially through one side of said rotatable member, a flanged pin on the other side member, the flange of said pin engaging in said recess for supporting

the other member from said rotatable member, said flange being slideable from said recess in one rotated position of said rotatable member whereby said snatch block may be opened at one end between said side members, said rotatable member formed with a pair of oppositely disposed flat sides, a supporting hook on said rotatable member, the shank of said hook engaging through the flat sides of said rotatable member, and means securing said hook on said latter member.
